PLANETARIUM

Vernon Chester Jones, Winnipeg, Manitoba,
Canada

Application April 13, 1939, Serial No. 267,738

8 Claims. (Cl. 58—3)

The invention has for its principal object, the visual indication of terrestrial time in hours and minutes completely around the earth, the portions of the earth in darkness and the portions 5 subject to sunlight at any given time, and the positions of both the sun and moon in relation to the equatorial part of the earth, including moon phases, and all such indications resulting from mechanical and automatic operations of the 10 working parts of said planetarium.

A further object of the invention is to provide means for manually adjusting the planetarium to position any geographically indicated part of the 15 earth to the uppermost point and such, that if said planetarium is located at such locality, said planetarium may be positioned in phase with the local points of the compass.

A further object of the invention is to provide 20 said planetarium with a celestial sphere, semi-automatic with the working parts of said planetarium and which may be operated to indicate the seasonable position of the sun and various heavenly bodies in their relation with the earth.

With the above important objects in view which 25 will become more apparent as the description proceeds, the invention consists essentially in the arrangement and construction of parts, herein-after more particularly described, reference being had to the accompanying drawings in which:

30 Figure 1 is a front elevation of the planetarium with a piece broken away to show the terrestrial semi-sphere.

Figure 2 is a plan view thereof.

Figure 3 is an enlarged vertical sectional view 35 taken on the line 3—3, Figure 1.

Figure 4 is a horizontal sectional view taken on the line 4—4, Figure 3.

Figure 5 is a vertical sectional view taken on the line 5—5, Figure 3.

40 Figure 6 is a reduced plan view of the minute disc.

Figure 7 is a reduced plan view of the cone shaped member covering the minute disc.

Figure 8 is a reduced diagrammatic view of 45 the hour dial in the flat.

Figure 9 is a reduced diagrammatic projection of the northern hemisphere of the celestial sphere.

In the drawings like characters of reference 50 indicate corresponding parts in the several figures.

The outer frame of the planetarium comprises a pair of side legs 1 and a rear leg 2 which support a semi-circular horizontal bar 3 and the frame is suitably re-enforced by cross members 4 55 connecting the side legs to the rear leg near the

bottom. An inner frame is formed from a T shaped piece of metal to provide a pair of side legs 5 and a rear leg 6. The side legs of the inner frame are suitably pivoted at 7 to the horizontal bar 3 while the rear leg 6 is provided with a series 5 of V shaped slots 8 on its periphery which are adapted to register with a set screw 9 on the rear part of the bar 3 in order that said inner frame may be pivoted and held in any desired position.

The lower ends of the legs 5 and 6 are fastened 10 to and support a circular casing 10 which carries the working parts of the planetarium. Two vertical plates 11 and 12 are suitably spaced and braced by rods 13 and the lower rods are fastened to the bottom of the casing 10 by screws 14. The 15 plate 11 carries an electric motor 15 on its outer face and said motor is started by a starting wheel 16 which projects through a hole in the casing 10. The current carrying wires for the motor are indicated at 17. The motor shaft drives a pinion 20 18 which, through a chain of gears 19, 20, 21, 22 and 23, drives a worm 24 which meshes with a central worm wheel 25. This worm wheel, in turn, drives a central vertical shaft 26 carried in bearings from plates 27 and 28 supported from 25 the vertical plates 11 and 12.

Above the plate 27, the shaft 26 carries a pinion 29 which meshes with a gear 30 rotatably supported on a plate 31 carried from the plate 27. The gear 30 drives a pinion 32 which meshes with 30 two gears 33 and 34. These two latter gears have a different number of teeth but the variation is so slight that they mesh satisfactorily with the pinion. The gear 34 drives a sleeve 35 mounted on the shaft 26 while the gear 33 drives a sleeve 35 35 mounted on the sleeve 35. The upper end of the sleeve 36 rotates a bar 37 which has one end curved downward and then looped upward and terminates in a disc 38. This disc represents the moon.

The upper end of the sleeve 35 carries an inverted cup shaped member 39 and the periphery thereof carries an upper series of progressive numbers from 1 to 24 and passing therearound while a lower series of progressive numbers from 1 to 12 passes half way around with the 1 under the upper number 13 and the 12 under the upper number 24. The numbers are also evenly spaced around the member and represent the hours of the day. Just below the number 12 on the upper series and partly cutting said number is a star which represents the sun. Below the sun is a circle with the letters N. M. to represent the words "new moon." Three other circles are evenly spaced around the member from this point with 55

the letters F. Q., F. M., and L. Q. to represent the words "first quarter," "full moon," and "last quarter" respectively. One-half of the periphery of the member is a dark color (represented by crosshatching) and the other half light to represent the hours of darkness and of light.

Above the cup shaped member 39, the shaft 26 is provided with a paper disc 40 which is fastened by a nut 41. The paper disc covers the upper 10 face of the cup shaped member, rotates with the shaft 26 and the edge of the face is provided with an annular row of progressive numbers 40' from 1 to 60 to represent the minutes in one hour.

The upper T shaped piece of metal, at the 15 junction of the legs 5 and 6, is forwardly slotted at 42 to receive the screw threaded end of a shaft 43 and this shaft is fastened thereto by a nut 44. The lower end of the shaft is connected to and supports a semi-sphere 45 which carries 20 a representation of the northern hemisphere of the world. This semi-sphere will later be referred to as the terrestrial semi-sphere. The semi-sphere 45 is hollow and contains a cone shaped member 46 having the upper end held 25 to the shaft 43 by a screw 47 while the bottom part contacts the lower edge of the semi-sphere 45 and projects over the annular ring numbers 40', except at one point where a cut-out 48 is provided. This cut-out represents the south 30 point of the compass and at equal distances around the cone shaped member the other points, east, north and west are printed.

Rotatable on the shaft 43 and surrounding the 35 semi-sphere 45, but spaced therefrom, is a further hollow semi-sphere 49 of Celluloid or other transparent material and which will later be referred to as a celestial semi-sphere. The lower edge of this semi-sphere frictionally contacts and covers the side of the circular cup shaped 40 member 39 and rotates therewith. This semi-sphere is provided with an encircling line 50 directly registering with an equatorial line 50' on the terrestrial semi-sphere. A further series 45 of encircling lines 51 are provided above the line 50 to mark off the celestial semi-sphere at intervals of 15°. The celestial semi-sphere is also marked off by twelve equi-spaced vertical lines 52 from the top centre down. An ecliptic line 50 53 is also indicated crossing the line 50 at two places which are marked by the months March and September. The other months are indicated in their proper places on the ecliptic line. The days of the month are also indicated by short 55 lines crossing the ecliptic line while the signs of the zodiac are positioned close to the months. A large number of fixed stars are also indicated, as at 54, in their proper position on the celestial semi-sphere and may be numbered so an observer 60 could look up a numbered index and find their names.

The lower part of the casing 10 is provided with two holes 55 which receive the anchored ends of a V shaped bar 56. A semi-sphere 57, 65 having a representation of the southern hemisphere of the world is positioned centrally on the bottom of the casing 10 and fastened to the V shaped bar 56 by a screw 58. This screw also holds rotatably, a further celestial semi-sphere 70 59 which is marked off in the same way as the upper celestial semi-sphere 49, but of course in correct orientation.

A registering pointer 60 is suitably fastened to the front face of the casing 10 and registers 75 with the hour numbers on the periphery of the

inverted cup shaped casing 39. Small strips of paper 61 will be glued or otherwise fastened around the lower edge of the upper terrestrial semi-sphere with names of various cities in different time zones around the world printed thereon.

In describing the operation, it will be assumed that the device is located at a specific point on the northern hemisphere of the earth. The nut 44 is released and the whole upper assembly, including the shaft 43, celestial semi-sphere 49, terrestrial semi-sphere 45 and the cone shaped member 46, is removed, the celestial semi-sphere sliding off the cup shaped member 39. The nut 41 is unscrewed and the operator can then lift 15 the member 39 up the shaft 26 until the gears 33 and 34 leave the pinion 32. The member 39 can then be rotated until the correct hour registers with the pointer 60. The member 39 is then dropped and the gears 33 and 34 re-mesh with 20 the pinion. At the same time the paper disc 40 is rotated until the correct minute is registering with the pointer, which is the point at which the cut-out 48 will be positioned. The motor 25 will then be connected to a source of time controlled power and started. The nut 41 is again fastened and the upper assembly, above mentioned, is re-inserted with the specific point of the northern hemisphere, above mentioned, directly in front and the cut-out 48 registering with the pointer 60. The inner frame and supported parts are then rotated on the pivot points 7 until the said specific point, above mentioned, is at the highest elevation and the set screw 9 is then 30 screwed in to hold the inner frame in that position. The planetarium is then positioned such, that the front will be facing in a south direction and when this is done all the other points of the compass will be in phase.

A still simpler method to set the time, which could be provided if desired, would be to connect the gear 34 to the sleeve 35 by a friction disc and the paper disc 40 to the shaft 5 by a further friction disc. The friction would be sufficient to drive the parts mentioned but the operator could then turn the cup shaped member 39 by hand without removing any parts and the paper disc 40 could be turned in the same manner. The two celestial semi-spheres will be turned until the sun, indicated by the star on the hour rim, is in registration with the day of the month shown on the ecliptic line. The moon 38 will also be set in its position around the hour rim to register with the proper moon phase. This is done by lifting the moon up slightly to clear the gear 33 from the pinion 32.

When the machinery is in operation the terrestrial semi-spheres and lower celestial semi-sphere will stay still. The disc 40 will rotate and give the correct minutes at the cut-out 48. The inverted cup shaped member 39 will rotate and give the correct hours at the registering pointer 60. The moon will rotate and register correctly its position with respect to the sun and also the different moon phases on the hour dial. The time, at any part of the earth can be observed by the registration of that particular part with the hour dial. The time in the various cities, the names of which are printed on the small strips of paper 61, will correspond with the time on the hour dial which registers with said strips. As the upper celestial semi-sphere is rotating with the hour dial, the various heavenly bodies indicated thereon will be in correct orientation.

tation with the earth and by observing the position of any star on said semi-sphere, its location in the sky can be ascertained at any time. Each day however, the celestial semi-sphere will be 5 manually rotated to advance it one day on the ecliptic past the sun to keep the earth in phase with the heavenly bodies. If at any time it is desired to observe the position of the heavenly bodies at the southern hemisphere, the lower 10 celestial semi-sphere can be rotated until its ecliptic exactly corresponds to the ecliptic on the upper celestial semi-sphere. It will then be in phase.

In Figure 1 it will be noticed that the ecliptic 15 lines of the two celestial semi-spheres are not in phase. This was done purposely to show the opposite part of the ecliptic, normally on the other side.

While it has been mentioned that the planetarium will register the earth time in minutes 20 and hours and be in phase with the various heavenly bodies, it will be understood that, if desired, the planetarium may be run at sidereal time using the same hours and minutes for the 25 reading. When this done, the sun and moon will not be in phase and therefore, can be removed. All the other parts will be in phase.

What I claim as my invention is:

1. A planetarium comprising: an adjustable 30 stationary semi-sphere; a rotatable semi-sphere enclosing said stationary semi-sphere; said stationary semi-sphere covered with a representation of a geographic hemisphere; said rotatable semi-sphere being transparent and provided with a representation of the heavenly bodies directly 35 above said geographic hemisphere; said semi-spheres pivotally mounted to rock at right angles to the axis of rotation of said rotatable semi-sphere; and means for locking said semi-spheres 40 in a number of such rocked positions; and means for revolving said rotatable semi-sphere at a constant speed.

2. A planetarium comprising: a stationary 45 semi-sphere covered with a representation of a geographic hemisphere; a rotatable transparent semi-sphere enclosing said stationary semi-sphere and provided with a representation of the heavenly bodies directly above said geographic hemisphere; an hour dial carrying a series of 50 evenly spaced progressive observable numbers; said hour dial rotatable with said rotatable semi-sphere; and means for rotating said hour dial at a constant speed.

3. A planetarium comprising: an adjustable 55 stationary semi-sphere covered with a representation of a geographic hemisphere; a rotatable transparent semi-sphere enclosing said stationary semi-sphere and provided with a representation of the heavenly bodies directly above said 60 geographic hemisphere; means for pivotally supporting said semi-spheres in a plane at right angles to the axis of rotation of said rotatable semi-sphere; means for locking said semi-spheres in various pivoted positions; and means for revolving said rotatable semi-sphere at a constant speed.

4. A planetarium comprising: a framework; a pair of telescoped semi-spheres pivotally supported by said framework; the inner semi-sphere 70 being adjustable and stationary and covered with a representation of a geographic hemisphere; the outer semi-sphere being transparent, revolvable, and provided with a representation of the heavenly bodies directly above said geographic hemisphere; an hour dial rotatable with

and adjustable with respect to said revolvable semi-sphere, and provided with a series of evenly spaced progressive observable numbers, each registerable with the different geographic longitudes on said stationary semi-sphere in the rotation of said hour dial; and means for rotating said hour dial at a constant speed. 75

5. A planetarium comprising: a stationary semi-sphere covered with a representation of a geographic hemisphere; a rotatable transparent 10 semi-sphere enclosing said stationary semi-sphere and provided with a representation of the heavenly bodies directly above said geographic hemisphere; an hour dial revolvable with said rotatable semi-sphere and provided with moon 15 phase indicating points therearound; an indicator revolvable around said hour dial and registerable with said moon phase indicating points in its passage therearound; and means for rotating said hour dial and said indicator at selected 20 time speeds.

6. A planetarium comprising: a stationary semi-sphere covered with a representation of a geographic hemisphere; said semi-sphere provided with an equatorial line; a rotatable transparent 25 semi-sphere enclosing said stationary semi-sphere and provided with a representation of the heavenly bodies directly above said geographic hemisphere; said rotatable semi-sphere provided with an encircling line directly registerable with the equatorial line on said stationary semi-sphere; said rotatable semi-sphere also provided with an ecliptic line crossing said encircling line and calibrated in months and days; an hour dial revolvable with said rotatable semi-sphere 30 and provided with a solar index registerable with the calibrations on said ecliptic line; said hour dial adjustable in respect to said rotatable semi-sphere to vary the registrations of said solar index with said ecliptic line calibrations; and means 35 for revolving said hour dial at a constant speed.

7. A planetarium comprising: an adjustable stationary semi-sphere covered with a representation of a geographic hemisphere; an hour dial rotatable around said stationary semi-sphere and 45 provided with a series of evenly spaced progressive observable numbers up to twenty-four; said latter numbers each registerable with the various geographic longitudes on said stationary semi-sphere as said hour dial rotates; a circular member 50 rotatable in respect to said hour dial; said circular member provided with a series of evenly spaced progressive numbers therearound up to sixty; a stationary member covering said circular member; an opening in said stationary member 55 through which said latter numbers are individually observable as said circular member rotates; said circular member adapted to rotate twenty-four times during a single rotation of said hour dial; and means for revolving said 60 hour dial and said circular member at selected time speeds.

8. A planetarium comprising: a framework; a pair of telescoped semi-spheres pivotally mounted to rock on said framework; the inner semi-sphere being stationary and covered with a representation of a geographic hemisphere; said stationary semi-sphere also provided with an encircling equatorial line; the outer semi-sphere being transparent, revolvable, and provided with 65 a representation of the heavenly bodies directly above said geographic hemisphere; an hour dial rotatable with said revolvable semi-sphere and provided with a series of evenly spaced progressive observable numbers up to twenty-four, each 70 75

- registerable with the different geographical longitudes on said stationary semi-sphere in the various rotated positions of said hour dial; said hour dial also provided with a solar index and with moon phase indicating points; a member rotatable in respect to said hour dial and provided with a series of evenly spaced progressive numbers up to sixty; a stationary member substantially covering said member and provided 10 with an opening for the individual observation of said latter numbers in the rotation of said rotatable member; said rotatable member adapted to rotate twenty-four times during a single rotation of said hour dial; said revolvable semi-sphere provided with an encircling line directly

registerable with said equatorial line on said stationary semi-sphere; an ecliptic line crossing said encircling line and calibrated in months and days and registerable with said solar index; said hour dial adjustable in respect to said rotatable semi-sphere to vary the registration of said solar index with said ecliptic line calibrations; a moon index revolvable around said hour dial and registerable with said moon phase indicating points in its passage therearound; means for revolving said hour dial, said rotatable member and said moon index at correct time speeds; and means for manually locking said semi-spheres in selected rocked positions on said framework. 10

VERNON CHESTER JONES. 15
